Primary Examiner — Dana L Meyrow(74) Attorney, Agent, or Firm — Walker, McKenzie & Walker, P.C.(57) CLAIM

The ornamental design for a bottle, as shown and described.

DESCRIPTION

FIG. 1 is a side elevation view of a bottle showing my new design, the opposing side being identical, excluding the unclaimed bottle pour spout;

FIG. 2 is a top plan view thereof; and,

FIG. 3 is a bottom plan view thereof.

The broken lines in the drawings illustrate the portions of the bottle that form no part of the claim.
